FIG. 1.

FIG. 2.

FIG. 3.

Inventors

William J. Rhodes
Kenneth Wollams

By Watson C. Coleman
Attorney

UNITED STATES PATENT OFFICE.

WILLIAM J. RHODES AND KENNETH WOLLAMS, OF WORTHINGTON, INDIANA.

WRENCH.

Application filed October 25, 1922. Serial No. 596,796.

To all whom it may concern:

Be it known that we, WILLIAM J. RHODES and KENNETH WOLLAMS, citizens of the United States, residing at Worthington, in the county of Greene and State of Indiana, have invented certain new and useful Improvements in Wrenches, of which the following is a specification, reference being had to the accompanying drawings.

10 This invention relates to wrenches, and more particularly to a quick adjustable wrench.

It is an object of the invention to provide a wrench of this character wherein the movable jaw can be adjusted to the size desired without the necessity of rotating any adjusting means or tightening the jaw after it is adjusted.

It is a further object of the invention to 20 provide a wrench of this character wherein the body member of the wrench substantially serves as a wedge in the tightening operation.

It is a still further object of the invention 25 to provide a device of this character wherein the adjusting means within the movable jaw and the movable jaw are both adapted for binding engagement with the body member of the wrench.

30 With these and other objects in view, the invention consists in the improved construction and arrangement of parts to be hereinafter more practically described, fully claimed and illustrated in the accompanying drawings, in which:—

Figure 1 is a side elevation of a wrench constructed in accordance with an embodiment of the invention, and showing the parts in the position they occupy when the 40 wrench is being adjusted;

Figure 2 is a section taken on the line 2—2 of Figure 1; and

Figure 3 is a side elevation showing the wrench in its set or adjusted position, one 45 of the connecting rings being shown in section.

Referring to the drawings, 5 designates an elongated body member or shank including a relatively broad front face 6 and a 50 relatively broad rear face 7. One end of the body member 5 is provided with a stationary jaw 8 which projects beyond the front face 6.

In connection with the body member and 55 the stationary jaw 8, a movable jaw member 9 is used, said jaw member comprising

an elongated block, the end 10 of said block serving as the jaw. The longitudinal edge 11 of the block is provided with a plurality of teeth 12, adapted to engage the front 60 face 6 of the body member. The opposite longitudinal edge 13 of the block is provided with spaced recesses 14 and 15. The lower end 16 of the block is curved inwardly toward the edge 11 to facilitate adjustment 65 of the wrench.

In connection with the movable jaw, a sliding member 17 is provided, said lever corresponding in width to the width of the rear face 7 of the body member. The member 17 is intended for sliding movement on the rear face of the body member and longitudinally of said face. One end portion of the member is provided with spaced recesses 18 and 19, said recesses extending 75 through the sides of the member.

In order to connect the lever to the movable jaw, connecting rings 20 and 21 are provided, each of said rings being substantially oblong in shape and slightly greater in 80 length than the distance between the recesses of the movable jaw member 9 and the member 17. The ring 20 is adapted to be disposed in the recesses 14 of the movable jaw member 9 and the recess 18 of the lever 19, 85 while the ring 21 is adapted to be disposed in the recess 15 of the movable jaw member 9 and the recess 19 of the member 17. A stop member 22 is carried by one side face of the jaw member 9 adjacent the recess 14 and 90 it is adapted to be engaged by the adjacent ring 20 whereby to hold the adjacent ring 20 and the ring 21 at right angles to the member 17, the jaw 9 and body member or shank 5, so that the member 17 and 95 movable jaw 9 may be adjusted without binding.

To adjust the wrench the member 17 is moved longitudinally of the body member so as to permit the ring 20 to engage the 100 stop 22. This positions the ring in a perpendicular position and permits the movable jaw member 9 to be moved longitudinally of the body member 5, together with the member 17. When the jaw member 9 has reached the desired point, or in other words, when the jaw member 9 comes in contact with the object to be tightened, the movement of the member 17 is continued by hand so as to substantially dispose the 105 rings 20 and 21 in an oblique position with respect to the side faces of the body mem-

2
ber 5. To break the binding engagement of the movable jaw and the sliding member it is only necessary to move the member longitudinally of the body member and 5 away from the stationary jaw 8 so as to permit the lever 20 to engage the stop member 22. This positions both rings substantially in a perpendicular position with respect to the axis of the body member 5, 10 thereby permitting both the member 17 and the movable jaw to be moved longitudinally of the body member unobstructedly to the desired point.

From the foregoing it will be readily 15 seen that this invention provides a novel form of wrench which can be quickly adjusted and maintained indefinitely in its adjusted position in view of the binding engagement of the lever and movable jaw on 20 the body member. In view of the fact that the movable jaw does not depend for its support on teeth or screws, it may be used for very heavy work without danger of the set position of the jaw being disarranged. 25 Furthermore, it may be adjusted to the exact size of the member to be tightened. It is of course obvious that we do not desire to limit ourselves to the particular form of jaws shown as both the work engaging 30 faces of the stationary jaw 8 and the movable jaw member 9 may be provided with teeth to permit the wrench to be used in connection with pipes or tubular objects. All of these features are possessed by a 35 structure which is simple and substantial and which can be manufactured from a small amount of material.

What is claimed is:—

1. A wrench comprising an elongated shank terminating at one end in a relatively 40 fixed jaw, a block slidably mounted upon one edge of the shank and having one end serving as a relatively movable jaw cooperating with said fixed jaw, an elongated actuating member slidably disposed against the 45 opposite edge of the shank, the outer edges of the member and block being formed with recesses, elongated loop-like elements engaged within said recesses and embracing the block, shank and member, and stop means on the block engageable by one loop 50 element for limiting swinging movement of both in one direction.

2. A wrench comprising an elongated shank terminating at one end in a relatively 55 fixed jaw, a block slidably mounted upon one edge of the shank and having one end serving as a relatively movable jaw cooperating with said fixed jaw, an actuating member slidably disposed against the opposite edge of the shank, the outer edges of the member and block being formed with 60 recesses, elongated loop-like elements engaged within said recesses and embracing the block, shank and member, and a pin 65 rigidly fixed to and projecting from the block and engageable by one loop element to serve as a stop for maintaining both loop elements in a position perpendicular to the shank whereby the member and block may 70 be slid freely along the shank.

In testimony whereof we hereunto affix our signatures.

WILLIAM J. RHODES.
KENNETH WOLLAMS.
